US0D1098060S

(12) **United States Design Patent** (10) **Patent No.:** **US D1,098,060 S**
(45) **Date of Patent:** **** Oct. 14, 2025**

(54) **PRECURSOR VESSEL NOZZLE**

(71) Applicant: **ASM IP Holding B.V.**, Almere (NL)

(72) Inventors: **Raghav Vishnu Rao**, Tempe, AZ (US); **Mojtaba Samiee**, Tempe, AZ (US); **Ali Aljanabi**, Scottsdale, AZ (US); **Shuyang Zhang**, Chandler, AZ (US); **Estiaque Haidar Shourov**, Mesa, AZ (US)

(73) Assignee: **ASM IP Holding B.V.**, Almere (NL)

(**) Term: **15 Years**

(21) Appl. No.: **29/927,439**

(22) Filed: **Feb. 5, 2024**

(51) **LOC (15) Cl.** **23-01**

(52) **U.S. Cl.**

USPC **D23/213**

(58) **Field of Classification Search**

USPC D23/200, 213, 223, 224, 226, 227, 228, D23/229, 249, 255, 259, 260, 499; D32/32, 1, 25; D15/144, 144.1, 199; D8/1, 2

CPC A61H 9/0021; A61H 9/0028; A61H 33/00; A61H 33/026; A61H 33/027; A61H 33/028; A61H 2033/021; B05B 1/00; B05B 1/005; B05B 1/02; B05B 1/04; B05B 1/042; B05B 1/044; B05B 1/046; B05B 1/048; B05B 1/06; B05B 1/12; B05B 1/14; B05B 1/08; B05B 9/00; B05B 9/01; C23C 16/44; C23C 16/455; C23C 16/45563; C23C 16/45565; C23C 16/45568; C23C 16/4557; C23C 16/45572; C23C 16/45578

(57) **CLAIM**

The ornamental design for a precursor vessel nozzle, as shown and described.

DESCRIPTION

FIG. 1 is a perspective view of a precursor vessel nozzle, showing my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

1 Claim, 7 Drawing Sheets
